UNITED STATES PATENT OFFICE.

RICHARD H. TATLOW, JR., OF DENVER, COLORADO.

LAMP.

1,227,694.

Specification of Letters Patent.

Patented May 29, 1917.

Application filed December 3, 1915. Serial No. 64,878.

To all whom it may concern:

Be it known that I, RICHARD H. TATLOW, Jr., a citizen of the United States, residing at Denver, in the county of Denver and 5 State of Colorado, have invented new and useful Improvements in Lamps, of which the following is a specification.

My invention relates to lamps, and particularly to headlights for use on automobiles, cars and the like.

The objects of my invention are to provide a lamp wherein is obtained the maximum efficiency from a source of light of a given candle power; to increase generally 15 the efficiency of the lamp by preventing loss of the light rays through diffusion and by utilizing such rays as would usually fall outside of the usual reflector of the lamp; to eliminate glare which is so objectionable 20 without impairing the efficiency of the lamp; to throw a beam of light downwardly within a relatively defined area so that the road bed in front of the automobile, or the like, to which the lamp is attached, may be suit- 25 ably lighted; to project the light rays directly forward substantially in parallelism with the focal axis of the lamp, so that the light is intensified, and the road is properly lighted; and to project the beam of 30 light in the form of a relatively narrow ribbon or band, so that while the beam of light is within relatively well-defined vertical limits relative to the focal axis of the reflecting surface, the beam is spread out somewhat 35 horizontally and the entire width of the road over which the automobile may be traveling is lighted.

The above and other objects of my invention are obtained in the structures de- 40 scribed in the following specification, and shown in the accompanying drawings, wherein—

Figure 1 is a side elevation of one embodiment of my improved lamp.

Fig. 2 is a front elevation thereof.

Fig. 3 is a top plan, while

Fig. 4 is a vertical sectional view taken longitudinally through the lamp shown in Fig. 1.

Fig. 5 is a side elevation partly in section showing a modified form of my improved lamp.

Fig. 6 is a longitudinal sectional view of a headlight showing one of the various embodiments of which my improved lamp is susceptible.

Referring to the drawings, wherein like parts are represented by like numerals, 10 designates the body or casing of my improved lamp which as shown particularly 60 in Fig. 2 is oval, or in the form of an ellipse in cross-section. The lamp is provided with suitable means for securing the same to the usual lamp supports, in the present case, such means being disclosed as apertured 65 ears 11, although it is to be understood that any other form of attaching means may be used. Within the body or casing 10 is a main reflector 12 which, as shown in Figs. 1 to 4, is preferably parabolic in curvature. 70 The source of light, in the present instance an electric-light bulb 13, is placed at the focal center of the parabolic reflecting surface so that those rays which strike the parabolic surface are reflected therefrom in 75 lines parallel with the focal axis of the reflecting surface 12 as is generally understood by those familiar with the subject of light. A chamber 14 is provided at the rear of my lamp between the walls of the 80 main reflector 12 and the casing 10, which serves to house the socket of the light 13 and wires leading thereto.

The front 15 may be secured in any suitable manner to the body 10 so as to be removable therefrom, in the present instance, lugs or ears 16 being provided on the body 10 in the apertures of which are carried the set screws 17, but this attaching means is shown by way of illustration only. The 90 front 15 is provided with a downwardly bent portion 18 which is disclosed in Figs. 1 to 4 as being curved outwardly, so that the concave portion of the reflecting surface 19 on the inside of said downwardly 95 bent portion is toward the source of light 13, the curvature of the reflecting surface 19 being such that light rays which ordinarily fall outside of the reflector 12 strike upon the reflecting surface 19 and are reflected 100 back substantially through the focal center of the parabolic reflector 12 where they merge into those parallel rays which are propagated through the light opening of the lamp. The lower portion 20 of the front 15 is curved upwardly and is provided with a reflecting surface 21 which intercepts those rays which ordinarily fall beneath the focal axis of the reflecting surface 12 and outside of this reflecting surface. 105

Between the edges of the downwardly and upwardly bent portions 18 and 20, respec-

tively, is a light opening 22 which, as will be readily noted from Fig. 2, is in the form of a horizontally extending elongated slot. It will be seen from Figs. 1 and 4 that 5 the upper downwardly bent portion 18 overhangs or extends beyond the lower upwardly bent portion 20, the object of this construction being to effectually intercept all rays extending above and at an angle to 10 the focal axis of the reflecting surface 12, while permitting the road-bed in front of the automobile to which the lamp is attached to be properly lighted. The rays of light pass through the light opening 22 in 15 the form of a ribbon or band, so that substantially the entire width of the road is lighted and all objects thereon are in clear view, while, to a certain extent, objects to either side of the road may be seen by the 20 driver of the automobile, and this is of particular importance where the driver of the automobile contemplates turning into a branch road.

The operation of my improved light will 25 be readily understood. The rays of light which are projected directly forward by the source of light 13 and those which strike that portion of the surface of the main reflector 12 which is in horizontal alinement 30 with the light opening 22 pass through the light opening in substantially parallel lines and in the form of a ribbon or band as heretofore described. Those rays of light which no not strike the reflecting surface 12 and 35 which in the usual form of light are wasted are intercepted by the upper downwardly bent portion 19 and are reflected back onto the reflector 12 and are again reflected thereby to the light opening or slot 22. Furthermore, those rays which strike the rays 40 of the reflector 12 out of line with the light opening, are reflected against the downwardly and upwardly bent portions on the front of the lamp and by these are again reflected back to the main reflector 12 and 45 then they are again reflected out through the light opening merging into the light rays which are projected in parallel lines. Thus substantially all of the rays of light 50 are bunched or gathered together and the effective light intensified; glare is eliminated; rays of light which are ordinarily wasted are used to advantage and a stronger and brighter light is obtained without increasing the candle power of the light. 55

As the upper downwardly bent portion 18 overhangs or extends beyond the edge 25 of the upwardly bent portion 20, the road-bed immediately in front of the automobile 60 is lighted, and glare due to upwardly extending rays is avoided. Some of the rays which strike the reflecting surface 19 (depending on the angle of incidence, as is readily understood) will be reflected not back 65 to the surface 12, but downwardly through

the light opening and onto the road, so that the road bed is lighted within fairly well defined limits, and the driver may avoid all holes, objects, and the like in the road. However, the rays which strike the surface 70 21 cannot escape immediately through the light opening 22 for should any rays of light be reflected upwardly and outwardly by the reflecting surface 21 they would fall upon and be intercepted by the reflector on 75 the overhanging and downwardly bent portion 18, which would reflect the rays back to the reflecting surface 12 in the manner above described.

In the construction shown in Fig. 5, it 80 will be noted that instead of extending the upper downwardly bent portion beyond the lower upwardly bent portion, these portions are substantially in the same vertical line and the lower upwardly bent portion is provided with a horizontal ledge or flange 23 85 extending inwardly of the lamp. The flange 23 constitutes a continuation of the upwardly bent portion, and the inner edge 25' of this flange is referred to in this embodiment of 90 the invention as the edge of the upwardly bent portion. It will be noted, that the downwardly bent portion of the headlight in the embodiment shown in Fig. 1 overhangs the edge 25 of the upwardly bent 95 portion; and in the embodiment shown in Fig. 5, the downwardly bent portion overhangs the edge 25' of the upwardly bent portion. It is to be understood that where the edge of the upwardly bent portion is 100 referred to in the claims, the term is of sufficient scope to include either of the edges 25 or 25' in the embodiments shown in Figs. 1 and 5, respectively. One of the salient features of this embodiment is that the 105 flange 23 extends inwardly of the lamp, and it is, of course, evident that this flange may be curved so that glare is prevented, and the light is reflected back through the center of the lamp. By this construction, all beams 110 of light striking the reflecting surface 21 below the flange 23 are intercepted by this flange and are prevented from escaping through the light opening 22 and thus those beams of light which otherwise would be 115 propagated upwardly at an angle to the parallel beams of light are caught, and glare so objectionable to the pedestrian especially when he is close to the automobile is eliminated.

It is, of course, to be understood that my headlight may take various forms, and as disclosing one of these embodiments, I show the structure shown in Fig. 6, wherein the casing 10 and the main reflector 12 are substantially conical instead of being parabolic, the light being placed in the apex of the casing and the chamber 14 being omitted. The front of the casing is provided with the elongated light opening 22, but instead of 120 125 130

curving the downwardly and upwardly bent portions they are straight, these portions being designated in the modification by numerals 18' and 20', respectively. If desired, the lower portion 20' may be in line with the upper portion 18', and it may be provided with a flange similar to that designated by the numeral 23, Fig. 5, or any other combination of the various features shown by me may be used.

While I have described my improved light as applied to an automobile, it may be used as a headlight on locomotives, street-cars, vehicles, and the like, and by placing numbers upon the transparent plate in the light opening 22, the lamp may be used as a tail-light for automobiles, and the like.

What I claim is:

1. In a lamp, a main reflecting surface, a source of light at the focal center of said surface, a downwardly bent portion on the front of the lamp adapted to intercept all rays projected upwardly at a given angle to the focal axis of the lamp, an upwardly bent portion on the front of the light for intercepting those rays which are projected directly from the source of light at a given angle downwardly to the focal axis of the lamp, and a light opening between said portions comprising a horizontally disposed elongated slot, said portions being so constructed that more upwardly extending rays are intercepted by the downwardly bent portion than downwardly extending rays by the upwardly bent portion, so as to eliminate

glare and permit some of the rays to be projected downwardly in front of the lamp.

2. In a lamp, a reflecting surface, a source of light, a downwardly bent portion, an upwardly bent portion, and a light opening between said portions, said downwardly bent portion being extended over the edge of said upwardly bent portion to intercept most of the rays extending upwardly at an angle to the focal axis of the lamp and to project some of the rays downwardly in front of the lamp.

3. In a lamp, a reflecting surface, a source of light, a downwardly bent portion on the front of the lamp and having a reflecting surface, an upwardly bent reflecting portion on the front of the lamp for intercepting those rays which are projected directly from the source of light at a given angle downwardly to the focal axis of the lamp, a light opening between said portions comprising a slot, and a flange along the upper edge of said upwardly bent portion extending inwardly of the lamp for intercepting those rays which are reflected upwardly at an angle to the focal axis of the lamp by the reflecting surface which lies substantially below said flange.

In testimony whereof I have hereunto set my hand in presence of two subscribing witnesses.

RICHARD H. TATLOW, JR.
